UNITED STATES PATENT OFFICE.

WARREN W. CARPENTER, OF QUEENS VILLAGE, NEW YORK, ASSIGNOR TO WESTERN ELECTRIC COMPANY, INCORPORATED, OF NEW YORK, N. Y., A CORPORATION OF NEW YORK.

RESTRICTED-SERVICE TELEPHONE-EXCHANGE SYSTEM.

Application filed April 27, 1927. Serial No. 186,904.

This invention relates to telephone exchange systems in which connections are established by means of automatically operated apparatus and has for its object the provision of improved means for controlling the scope of the service granted to the subscribers.

It is customary to group the subscribers' lines incoming at a telephone exchange in accordance with the service to which they are entitled; direct lines, party lines, lines equipped with coin boxes, lines entitled to only restricted service, etc., constituting separate groups. In the past these groups of subscribers have been served by separate groups of senders. In the case of senders serving subscribers who were entitled to restricted service only, the setting of the registers for restricted groups was employed to cause the connection of the line to an operator's position. According to this arrangement there could be only two classes of offices, those to which the restricted subscribers could be connected and those to which they could not be connected. In order to discriminate more closely it was necessary to make additional groups and provide additional senders.

In accordance with the present invention the subscribers' lines are grouped in accordance with the class of service to which they are entitled at the basic rate and the arrangement is characterized by the fact that provision is made in senders, common to all classes of subscribers' lines, to record the class of service to which a calling line is entitled and in conjunction with zoning relays, which are set in accordance with the office code dialed by the calling subscriber, to determine whether the call shall be routed into the zone into which the subscriber has dialed or rerouted to a special trunk.

The embodiment of the invention described hereinafter by way of example, provides, specifically stated, a coordinate switching system employing senders and markers which are associated with a calling line and associated district selector for the purpose of controlling the operation of the selector in accordance with the registration set up in the sender from the subscriber's dial. The markers are associated with the district selectors by means of a

district frame connector which includes relays individual to each district frame to which the connector has access. Since the group of district frames is individual to the group of lines served thereby, the relay in the frame connector may be employed to identify the class of line over which a particular call originated. The registration of the office code of the wanted subscriber causes the operation of a routing relay in the marker and in the case of non-local offices a zoning relay is also operated. In the case of lines whose service is restricted the joint operation of the zoning relay and the frame connector relay causes the release of the routing relay corresponding to the dialed code and the operation of another routing relay which will cause the connection of the subscriber's line to a trunk to an operator's position. Where the subscriber's service is not restricted no such cooperation takes place and the routing relay functions.

Both the general and specific aspects of the invention will be more clearly understood from consideration of the following description in connection with the drawings in which:

Fig. 1 shows the calling subscriber's line, a line switch, a sender selector, a sender and a sender connector all in diagrammatic form;

Fig. 2 shows a circuit of one trunk outgoing to a district selector;

Fig. 3 shows a district selector switch;

Fig. 4 shows a trunk outgoing to an office selector;

Fig. 5 shows an office selector;

Fig. 6 shows a group of relays in the marker for testing the trunks of a trunk group;

Fig. 7 shows the registers of the marker;

Fig. 8 shows the district frame connector and the district trunk connector;

Fig. 9 shows a translator which determines the routing relay to be operated;

Fig. 10 shows the office frame connector and the office trunk connector;

Fig. 11 shows the routing and zoning relays; and

Fig. 12 shows the manner in which Figs. 1 to 11 inclusive should be arranged.

In general the system and apparatus employed in the present disclosure are the same

as those disclosed in U. S. Patent 1,600,399, granted September 21, 1926 to W. W. Carpenter and reference is made thereto for a more complete showing and description of such a system.

Line 101 represents one of a group of lines entitled to the same class of service. When the subscriber thereat initiates a call the line will be extended through line switch 100 to a trunk such as trunk 116 leading to one of a group of district selectors serving this particular group of lines such as district selector 300. The operation of the line switch 100 in turn initiates the operation of sender selector 150 to associate an idle sender with trunk 116. When the connection of an idle sender such as sender 170 to the trunk has been completed ground is connected to conductor 214 operating relays 200 and 206 in parallel. Relay 206 at its right front contact supplies ground to conductor 211 to hold the line switch operated. Relay 200 in operating opens the circuit of relay 204 and extends the tip and ring conductors from the calling line to the impulse receiving mechanism of the sender. Relays 205 and 212 have also been operated as described in the above identified patent.

The subscriber now dials the number of the wanted subscriber and this number is recorded in the sender. A record is likewise made in the sender of the group of district selectors to which selector 300 belongs. As soon as the office code, represented by the first three digits dialed, has been recorded, the sender connector 160 is actuated to connect the sender with an idle outgoing marker. For simplicity the conductors extending from the connector 160 to the marker have been grouped and are represented by brackets and the heavy dotted line 180. The above mentioned operations also take place in the manner disclosed in the above identified patent.

As soon as the sender is connected to the marker, the sender connects battery to conductor 913, which extends to the winding of relay 908 and ground so that relay 908 operates. The operation of the sender connector 160 also establishes circuits from ground over the front contacts of the operated relays of the code registers of the sender to the windings of the corresponding relays of the marker registers 700, 701 and 702 to transfer the code registrations from the sender registers to the marker registers.

At the same time a circuit is closed from ground over the back contact of relay 911, conductor 950, through sender connector 160, over the back contacts of all unoperated relays of the sender registers and back over connector 160, through the windings of the remaining relays of registers 700, 701 and 702 in parallel to battery. The relays of these registers operate, closing a series cir-

cuit from battery through the winding of relay 910 and thence through the contacts of all the marker register relays in series, over the left back contact of relay 909 to ground at the outer right front contact of relay 908. Relay 910 locks over its left front contact, back contact of relay 912, back contact of relay 909 to ground at the outer right front contact of relay 908. Relay 910 in operating closes an obvious circuit for operating relay 911 which removes ground from conductor 950. Relay 911 also operates relay 912 and relays 912 and 911 lock over the left front contact of relay 911 and the back contact of relay 909 to ground at the contact of relay 908. The operation of relay 912 opens the locking circuit of relay 910 causing that relay to release. The removal of ground from conductor 950 permits those marker relays which do not correspond to operated sender relays to release. Let it be assumed that relays 703, 704, 706, 708, and 712 are held operated.

The next step is to operate the translator 900 from the register relays in the marker to select one or more of the routing relays shown in Fig. 11, each of which relates to a different one of the groups of trunks outgoing from the district and office selector switches.

The register 700 with the setting given causes the operation of multi-contact relay 903 in a circuit from battery through the winding of said relay, thence through the inner right front contact of relay 704, outermost right front contact of relay 706, inner right front contact of relay 703, conductor 717, back contact of relay 910, front contact of relay 912, back contact of relay 909, front contact of relay 908 to ground. The register 701 with the setting given causes the operation of relay 905 in a circuit traceable from battery through the winding of said relay, thence over the middle right back contact of relay 707, inner left front contact of relay 708, the outer right back contact of relay 709, back contact of relay 710 to the grounded conductor 717. With the translator 900 set, a circuit is completed from grounded conductor 717 through the right back contact of relay 714, outer right back contact of relay 713, inner left front contact of relay 712, outer right back contact of relay 711, conductor 919, contact of relay 905, contact of relay 903, conductor 951, through the distributing frame 1113 to the winding of relay 1193 and battery. Relay 1193 connects ground over its outer left front contact to the windings of relays 1106 and 1107.

While the foregoing operations have been taking place the outgoing marker has also been in the act of associating itself with the proper group of district selector frames by means of the corresponding one of the frame

connectors 800 and 801. The instant the sender is connected to the outgoing marker, the record set up in the sender of the group to which district selector 300 belongs, causes district frame connector relay 609 to be operated. This relay relates to the frame connector 800 and when operated instructs the marker that it must use that particular frame connector for selecting the proper group of district selectors. The other frame connector relay 610 similarly relates to the frame connector 801. Relay 609 gives this instruction by closing a circuit for relay 804, which is individual to the marker shown, at the district frame connector 800. This circuit may be traced from battery through the inner left contact of relay 908, conductor 918, right contact of relay 602, contact of relay 609, right winding of relay 804 to ground at the contact of relay 805. Relay 804 operates and locks in a circuit through its left winding and locking contact, left back contact of relay 820, winding of relay 805 to ground. Relay 805 also operates and prevents any other marker from appropriating the frame connector 800. Relay 805 closes an obvious circuit for the multi-contact relay 806 which extends the various leads from the marker through to the grid wires of the connector 800.

The vertical operating magnet 310, individual to the row of contacts 301 of the selector 300, in which the trunk 116 appears, is now operated. The circuit for this purpose may be traced from battery through the winding of said magnet, conductor 318, outer right contact of relay 215, upper front contact of relay 200, thence over conductor 216 through the sender selector 150, through the sender connector 160, through the cable 180 to conductor 719, left bank contact of relay 606, conductor 632, inner right contact of relay 804 to ground at the front contact of relay 805. It will be noted that the relay 611 also operates in parallel with the vertical magnet 310. Magnet 310 prepares the contacts of the vertical row 301. It also operates the multi-contact relay 809, individual to the switch 300, in a circuit from battery through the winding of said relay, inner front contact of magnet 310, and thence over conductor 318 to ground as above traced. Relay 809 connects the grid wires of the frame connector 800 to the conductors leading to the switch 300. With the frame connector 800 operated, the vertical magnet 310 and relay 809 are locked in parallel circuits extending through the frame connector, thence over conductors 821 and 633, left contact of relay 603, conductor 720 to ground at the inner right contact of relay 908.

Relay 215 is also operated at this time in a circuit from battery through its left winding, conductor 217, lowermost contact of magnet

310, contacts of frame connector 800 to ground. Relay 215 locks through the left front contact of relay 206 to grounded conductor 211.

Since the multi-contact relays 808, 809, etc., are each individual to a district selector switch such as 300 the identity of this switch may be established by the frame connector 800 for the purpose of determining which one of the routing relays shown in Fig. 11 should be operated. It will be recalled that in the present case both relays 1106 and 1107 were prepared for operation. Only one of these, however, is needed, which is the one that is individual to the group of trunks appearing in the district selector frame 300. Accordingly, relay 808 has certain of its contacts arbitrarily wired to ground, one of which identifies the district selector frame 300 for this purpose. Accordingly, relay 1111 is operated in a circuit traceable from battery through the winding of said relay, conductor 1012, through the contacts of the frame connector 800 to ground. Relay 1111 completes a circuit for operating routing relay 1106 to the exclusion of relay 1107. This circuit may be traced from battery over the inner contact of relay 1111, thence through the winding of relay 1106 to ground at the front contact of relay 1193.

With relay 1106 operated, relay 643 is operated in a circuit from battery through the winding of the latter relay, thence over the conductor 644 to ground at the contact of relay 1106. Relay 643 locks to the grounded conductor 720. Relay 638 is operated in turn in a circuit from battery through its winding, outer left contact of relay 643, conductor 645, left back contact of relay 909, to ground at the contact of relay 908. Relay 638 serves to delay the notification of the sender to release from the marker until after the office selector switch has been operated, as will appear hereinafter, since relay 1106 represents a routing through an office selector. Relays 1193 and 1106 also cause the operation of certain class relays in the sender which govern the completion of the connection at the distant office.

Since the routing relay 1106 has been selected and operated the necessary information is available for telling the marker with which group of trunks leading from the district frame it should make connection. With relay 1106 operated, a circuit is closed for relay 811, which is individual to the selected marker at the trunk connector 802, extending from battery, inner left contact of relay 908, conductor 918, right contact of relay 602, contact of relay 611, conductor 1114, inner right contact of relay 1106, conductor 822, right winding of relay 811, back contact of relay 812 to ground. Relay 811 locks through its left winding to ground in

series with the winding of relay 812 and relay 812 also operates. Multi-contact relay 813 is operated next in a circuit over contacts of relays 811 and 812. Relay 813 connects the various conductors from the marker to the common grid wires of the trunk connector 802.

The next step is to operate the particular one of the multi-contact relays 815, 816, etc., which represents the group of trunks to which the marker is to be connected. In the present case the group of trunks appearing in the vertical row 305 of the district selector is represented by the relay 815 and this relay is operated directly from a contact of the routing relay 1106 in the marker. The circuit therefor may be traced from battery through the winding of relay 815, conductor 832, outer right contact of relay 1106, conductor 1115 to ground through contacts of relays 811 and 812. Relay 815 connects the grid wires of the connector 802 to the conductors leading to the test conductors of the several trunks in the proper group.

Since the multi-contact relay 815 is individual to the row of contacts 305 its operation may be made to cause the operation of the vertical magnet 313. The circuit for this purpose may be traced from ground through the contact of relay 815, thence through a contact of relay 813, conductor 825, right contact of relay 603, conductor 634, middle right contact of relay 1106, conductor 1013, through the frame connector 800, thence through the winding of magnet 313 to battery. Magnet 313 prepares the contacts in the vertical row 305 and also operates relay 606 in the marker. The circuit for relay 606 may be traced from ground through the contact of magnet 313, conductor 319, through the frame connector 800, conductor 827, winding of relay 606 to battery. Relay 606 locks over its inner right contact to the grounded conductor 720.

The marker has thus been connected to the district frame and the trunk group outgoing therefrom and the apparatus is now in condition to test the horizontal links in the district switch and the corresponding outgoing trunks. This operation being fully described in the above identified patent, it will merely be assumed that link 308 and trunk 402 are the first to be idle and that in consequence relays 620 and 622 are operated while relay 624 remains inert. Relay 625 is therefore operated in a circuit from battery through the winding thereof, left back contact of relay 624, left front contacts of relays 622 and 620 in series, conductor 635 through the trunk connector 802 to the distributing frame 824 and returning through the trunk connector to conductor 829, outer right contact of relay 606, left back contact of slow relay 602 to the grounded conductor

720. Relay 625 opens the operating circuits of relay 624 and closes a circuit for horizontal operating magnet 316 from battery through the winding of said magnet, conductor 324, through the connector 800, conductor 830 to ground at the outer contact of relay 625. Magnet 316 effects the connection through the district switch 300, thereby extending the trunk 116 to the selected idle outgoing trunk 402.

This connection having been established, a test is made which involves contact points on district selector switch 300 to make sure that the switch is properly operated. For this purpose a circuit is closed from battery through the winding of relay 604, left back contact of relay 605, thence through the inner front contact of relay 625, conductor 637, through the trunk connector 802, conductor 831, operated contacts of switch 300 to the grounded sleeve conductor 211 of trunk 116. Relay 604 locks and closes obvious circuits for operating relays 602 and 603. Relay 603 at its right contact opens the circuit of the vertical magnet 313 which releases. At its left contact relay 603 opens the holding circuits of the operated test relays in the marker and also opens the holding circuits of vertical magnet 310 and multi-contact relay 809.

Relay 602 releases the relays 811 and 812 which in turn cause the release of relay 813. Relay 602 also releases relay 625 which opens the operating circuit of magnet 316. In addition, relay 602 opens the circuit of relays 804 and 805, in turn causing the release of relay 806. The relay 811 in releasing releases the multi-contact relay 816. Thus, the outgoing marker is disconnected from the district frame 300 by the release of the frame connector 800 and from the group of trunks by the release of trunk connector 802. The connection through the district selector frame 300 is held by the maintained operation of horizontal relay 316 which is locked in a circuit from battery through both windings in series, thence through contacts of switch 300 to the grounded conductor 211. Relay 602 also extends ground from conductor 720, over its front contact to the back contact of relay 638. Were relay 638 not operated, conductor 660 would be grounded, completing a circuit through the timing device 730 to the sender to cause the disconnection of the marker from the sender. Since, however, relay 638 is operated this circuit is not closed and the marker remains connected with the sender.

In case a group of trunks leading from the district frame to the office frame is larger than a single vertical row of contacts on the office frame can accommodate, they may be arranged in two or more sub-groups. In order to distinguish the particular sub-group involved, all the trunks of a common sub-

group are identified by a characteristic circuit connected to the contact of relay 400, there being one of these relays for each trunk in the group. In the present case a low resistance 401 is connected to the back contact. For a second sub-group the resistance 401 would be high. As soon as the connection is established over the district frame 300 a circuit is closed from ground through 10 the low resistance 401, inner back contact of relay 400, thence over the ring side of trunk 402, through the district selector switch 309, conductor 220, through the sender selector switch 150 and the sender connector 160 to conductor 722, outer back contact of relay 601, windings of relays 640 and 641 to battery. Since the resistance 401 is low, both the marginal relay 640 and the relay 641 operate. These relays lock to the 20 grounded conductor 720. Relay 641 operates relay 642 which also locks to conductor 720.

The operation of relays 640, 641 and 642 initiates the connection of the marker with the office selector 500 to which trunk 402 25 extends. For this purpose a circuit is closed from ground, over the back contact of relay 1003, right winding of relay 1002, which is individual to the marker in office frame connector 1000, conductor 1014, right contact of relay 643, right front contact of relay 640, left contact of relay 642, right contact of relay 607 to battery over conductor 918. Relay 1002 locks in series with relay 1003 and the two jointly cause the operation of 35 multi-contact relay 1004.

The vertical magnet 509 of the office selector switch 500 is now operated in a circuit from battery through the winding thereof, conductor 512, outer back contact of relay 400, over the tip of the trunk through the district selector switch, and over conductor 216 as previously traced, through the sender connector 160 to conductor 719, and thence over the inner left front contact 40 of relay 606, left contact of relay 601, conductor 646, contacts of relay 1002 and 1003 to ground. Relay 612 is also operated in parallel with the circuit above traced. The magnet 509 prepares the contacts of the 45 vertical row 502 and also operates the multi-contact relay 1006 which is individual to the particular office selector frame 500. The circuit for this latter relay may be traced from battery through the winding thereof, thence over the contact of magnet 509, to ground over conductor 512. The magnet 509 and relay 1006 lock in circuits through their windings, thence over a path through the office frame connector 1000, conductor 55 1015, through the left contact of relay 608, left front contact of relay 602, to the grounded conductor 720.

Relay 612, which operates when the frame connector 1000 operates, closes an energizing 60 circuit for the relay 1007 of the office trunk

connector 1001. This circuit may be traced from ground through the back contact of relay 1008, right winding of relay 1007, conductor 1016, thence through the inner right contact of relay 1193, conductor 1121, 70 contact of relay 612, through the right contact of relay 607 to battery over conductor 918. Relay 1007 operates and locks through its left winding and the winding of relay 1008, and the latter relay also energizes. 75 Relays 1007 and 1008 jointly operate the multi-contact relay 1009.

Assume that the group of trunks leading to the desired office appear in the vertical row 504 of the office selector switch 500 and 80 that the relay 1017 is individual to this particular group. Relay 1017 accordingly is operated in a circuit traceable from battery through the winding thereof, conductor 1018, through the outer right contact of relay 1193, conductor 1022, through contacts of relays 1007 and 1008, to ground. Relay 1017 operates relay 1010, whereby the test conductors of the trunks in the outgoing group are connected through to the 85 test relays 600 of marker.

The vertical operating magnet 511 is next energized by means of a circuit from battery through its winding, thence over conductor 513, through the frame connector 95 1000, conductor 1019, through the middle right contact of relay 1193, thence over conductor 1123 through the right contact of relay 608, conductor 647, through contacts of the frame connector 1001 to ground. It will 100 be noted that relay 605 operates in parallel with the circuit just traced. The magnet 511 prepares the contacts in the vertical row 504 and also operates relay 601 in a circuit traceable from battery through the winding 105 of said relay, conductor 648, through the frame connector 1000, to ground at the contact of magnet 511.

The horizontal links 505, 506, 507, 508, etc., of the office switch 500 and the corresponding trunks of the outgoing groups are 110 tested by means of the test relays in the marker in exactly the same manner as disclosed in connection with the district selector 300. Assume that the link 508 and the corresponding trunk 514 are both idle and that no preceding trunk and its corresponding link are both idle. Accordingly, relays 620, 622 and 624 are all operated and relay 626 is the first one in the series to remain 115 deenergized. Relay 627 is next operated in a circuit from battery through its winding, left back contact of relay 626, left front contacts of the test relays, thence over conductor 635, through the office trunk connector 1001, through the inner left contact of relay 1017, and returning over the contacts of the office trunk connector, conductor 829, outer right contact of relay 601, left contact of relay 607, left front contact of relay 602, 120 125 130

to grounded conductor 720. Relay 627 at its outer right contact closes a circuit through the frame connector 1000 for the horizontal magnet 515. Magnet 515 locks 5 through its windings and contacts of switch 500, thence over conductor 403, through the relay 400 and the district selector switch 300 to ground on the sleeve conductor 211 of the trunk 116. Relay 400 operates and completes the tip and ring conductors of the trunk and opens the operating circuit of the vertical magnet 509.

The connection through the office switch has thus been established and the marker may now be released. This is accomplished by operating relay 650 in a circuit from battery through the winding thereof, left front contact of relay 605, conductor 651, inner right contact of relay 627, conductor 652, through the trunk connector 1001, through the contacts of switch 500 to ground on conductor 403. This circuit provides a test to ascertain whether the office frame has completed the connection. Relay 650 10 locks through its right front contact and operates relays 607 and 608. These relays bring about the release of the office frame connector 1000 and the office trunk connector 1001, whereby the marker is disconnected 15 from the office switch. Relay 607 also connects ground to conductor 660 from the front contact of relay 602 thus causing the sender to release the sender connector 160. The outgoing marker is thus disassociated from 20 the sender and restored to common use. The vertical magnets 509 and 511 of the office switch are released and the connection thereover is maintained by the continued energization of the horizontal magnet 515.

40 The completion of the connection to the called subscriber takes place as described in the above identified patent.

Restricted calls.

45 It is of course customary to permit subscribers to make calls at the basic rate only over a limited area and to make an additional charge for calls to offices at a greater distance. It may be desirable to permit 50 certain subscribers who pay a higher basic rate to make calls over a larger area than others. The offices are therefore grouped in zones and the subscribers are grouped according to the zones to which they are entitled to be connected at the base rate. The 55 district selectors are made individual to the particular class of service group. Therefore, since the relays, such as relays 808 and 809 in the district frame connector 800, are individual to the particular district frames, it 60 is possible to identify the class of service to which a calling line is entitled by means of contacts on relays 808 and 809 in the frame connector. Zone relay 1193 which was operated in connection with the above traced call

represented a zone to which all subscribers had access but which was reached from the office selector, relay 1106 controlling the selection of a group of trunks outgoing to an office selector.

Had the subscriber dialed a code such that zone relay 1108 had been operated, relay 1109 would have been operated and the circuits for relays 1106 and 1107 would have been prepared. The operation of trunk connector 800 is independent of the setting of the registers and takes place at the same time as registration. Therefore when relays 809 and 1108 have been operated a circuit is closed from ground over the contact of relay 809, through the frame connector, conductor 860, outer right contact of relay 1108, conductor 1150, winding of relay 909 to battery. Relay 909 locks over its left front contact to the outer right front contact of relay 908. At its left contact relay 909 closes a circuit from ground over the outer right front contact of relay 908, right contact of relay 909, conductor 960, winding of routing relay 1103 to battery. At its left contact relay 909 opens the locking circuit of relays 911 and 910 and disconnects ground from conductors 645 and 717. The removal of ground from conductor 717 releases the relays of translator 900 in turn releasing relays 1108 and 1109 and removing ground from the windings of relays 1106 and 1107. The routing corresponding to the code dialed has therefore been cancelled and a new routing set up which leads to a special trunk appearing 100 at an operator's position.

The functioning of the marker to select this trunk is essentially the same as in selecting any other trunk group, the control being assumed by relay 1103. Therefore 105 these operations will not be described in detail. However, since talking battery is usually supplied, when a connection is established to an operator's position, from the operator's cord, means is provided for 110 disconnecting repeating coil 202. For this purpose a circuit is established from ground over the middle left contact of relay 1103 to conductor 832, through the frame conductor 800, conductor 327, middle lower contact of 115 magnet 310, conductor 221, upper winding of relay 201 to battery. Relay 201 locks over its inner upper front contact to conductor 211. It disconnects the tip and ring conductors incoming from the subscriber's 120 line from the repeating coil 201 and extends them directly to the tip and ring conductors outgoing to the district selector.

From an inspection of the circuits it will appear that relay 1191 represents a zone to 125 which the subscribers corresponding to relay 809 would have free access. The subscribers belonging to the group represented by relay 808, however, are restricted from making calls to the zone corresponding to either 130

relay 1108 or 1191. It is therefore possible by this arrangement to provide as many grades of service as desired.

What is claimed is:

5. 1. In a telephone system, subscribers' lines of a plurality of classes, a control device for controlling the establishment of connections from all classes of said lines, means for associating said control device with a calling line, 10 selective means in said device under the control of said calling line, means for identifying the class to which said calling line belongs, and means under the joint control of said selective means and said identifying means to determine the manner in which said connection shall be completed.
15. 2. In a telephone system, subscribers' lines of a plurality of classes, a control device for controlling the establishment of connections from all classes of said lines, means for associating said control device with a calling line, means in said device under the control of said calling line for recording the designation of a wanted office, means for identifying the class to which said calling line belongs, and means under the joint control of said recording means and said identifying means to determine whether or not said connection shall be completed to the 25 wanted office.
30. 3. In a telephone system, subscribers' lines of a plurality of classes, an operator's position, a control device for controlling the establishment of connections from all classes of said lines, means for associating said control device with a calling line, means in said device under the control of said calling line for recording the designation of a wanted office, means for identifying the class to which said calling line belongs, and means under the joint control of said recording means and said identifying means to determine whether said connections shall be completed to the wanted office or to said operator's position.

35. 4. In a telephone system, subscribers' lines of a plurality of classes, a control device for controlling the establishment of connections from all classes of said lines, means for associating said control device with a calling line, means under the control of said calling line for recording the designation of a wanted office, means operated in accordance with said record for controlling the extension of a connection from said calling line to said office, and means under the control of said recording means effective if the calling subscriber's line is of a particular class to render said extension controlling means ineffective.
40. 5. In a telephone system, subscribers' lines of a plurality of classes, an operator's position, a control device for controlling the establishment of connections from all classes of said lines, means for associating said control device with a calling line, means under

the control of said calling line for recording the designation of a wanted office, means operated in accordance with said record for controlling the extension of a connection from said calling line to said office, and means under the control of said recording means effective if the calling subscriber's line is of a particular class to render said extension controlling means ineffective and for operating other means for controlling the extension of said connection to said operator's position.

6. In a telephone exchange system, a plurality of offices located in a plurality of zones, subscribers' lines terminating at one of said offices and grouped according to the zones to which they are permitted to have access, selective switches for extending connections from said lines to lines in the same or other offices, a controlling device at said one office common to all groups of lines, a plurality of routing relays in said device, means for operating one of said relays in accordance with the zone in which the wanted office lies, means operative under the control of said relay, if said calling line belongs to certain groups, to direct the operation of said switches, and means effective if said calling line belongs to other groups to release said relay and to operate a different relay.

7. In a telephone exchange system, a plurality of offices located in a plurality of zones, subscribers' lines terminating at one of said offices and grouped according to the zones to which they are permitted to have access, selective switches for extending connection from said lines to lines in the same or other offices, a controlling device at said one office, common to all groups of lines, means for setting up a registration on said device in accordance with the designation of a wanted office, means operative in accordance with said registration to direct the operation of said selector switches, means effective if said calling line belongs to certain groups to complete the connection to the wanted office, and means effective if said calling line belongs to other groups to cancel said registration and to set up a different registration.

8. In a telephone exchange system, a plurality of offices located in a plurality of zones, subscribers' lines terminating at one of said offices and grouped according to the zones to which they are permitted to have access an operator's position, selective switches for extending connections from said lines to lines in the same or other offices, a controlling device at said one office common to all groups of lines, means for setting up a registration in accordance with the designation of a wanted office, means operative in accordance with said registration to direct the operation of said selective switches,

means effective if said calling line belongs to certain groups to complete the connection to the wanted office, and means effective if said calling line belongs to other groups to cancel said registration and to set up a registration to direct the operation of said switches to extend the calling line to said operator's position.

9. In a telephone exchange system, a plurality of offices located in a plurality of different zones, subscribers' lines terminating at one of said offices and grouped according to the zones to which they are permitted to have access, selective switches for extending connections from said lines to lines in the same or other offices, a controlling device at said one office common to all groups of lines, means for setting up a registration on said device in accordance with the designation of a wanted office, means operative in accordance with said registration to direct the operation of said selector switches, means in said device for identifying the group of subscribers to which a calling line belongs, and means under the joint control of said registration and said identifying means to cancel said registration and to set up a different registration.

10. In a telephone exchange system, a plurality of offices located in a plurality of different zones, subscribers' lines terminating at one of said offices and grouped according to the zones to which they are permitted to have access, selective switches for extending connections from said lines to lines in the same or other offices, a controlling device at said one office, common to all groups of lines, means for setting up a registration on said device in accordance with the zone in which the wanted office lies, means operative in accordance with said registration to direct the operation of said selector switches, means in said device for identifying the group of subscribers to which a calling line belongs, and means under the joint control of said registration and said identifying means to cancel said registration and to set up a different registration.

11. In a telephone system, subscribers' lines of a plurality of classes, selector switches for extending connections from said lines, means for connecting a calling line to one of said switches, a control device common to all classes of said lines for controlling said switch, means for associating said control device with said switch, selective means in said device under the control of said calling line, means in said device under the control of said associating means for identifying the class to which the calling line belongs, and means under the joint control of said selective means and said identifying means to determine the manner in which said connections shall be completed.

12. In a telephone system, subscribers'

lines of a plurality of classes, selector switches for extending connections from said lines, means for connecting a calling line to one of said switches, a control device common to all classes of said lines for controlling said switch, means for associating said control device with said switch, means in said device under the control of said calling line for recording the designation of a wanted office, means in said device under the control of said associating means for identifying the class to which said calling line belongs, and means under the joint control of said recording means and said identifying means to determine whether or not said connection shall be completed to the wanted office.

13. In a telephone system, subscribers' lines of a plurality of classes, selector switches for extending connections from said lines, means for connecting a calling line to one of said switches, an operator's position, a control device common to all classes of said lines for controlling said switch, means for associating said control device with said switch, means in said device under the control of said calling line for recording the designation of a wanted office, means in said device under the control of said associating means for identifying the class to which said calling line belongs, and means under the joint control of said recording means and said identifying means to determine whether said connection shall be completed to the wanted office or to said operator's position.

14. In a telephone system, subscribers' lines of a plurality of classes, selector switches for extending connections from said lines, means for connecting the calling line to one of said switches, an operator's position, a control device common to all classes of said lines for controlling said switch, means for associating said control device with said switch, means under the control of said calling line for recording the designation of the wanted office, means operated in accordance with said record for controlling the extension of a connection from said switch to said office, means under the control of said associating means for identifying the class to which said calling line belongs, and means effective if said calling line is of a particular class to render said extension controlling means ineffective, and for operating other means for controlling the extension of said connection to said operator's position.

15. In a telephone exchange system, a plurality of offices located in a plurality of zones, subscribers' lines terminating in one of said offices and grouped according to the zones to which they are permitted to have access, selector switches for extending connections from said lines, means for connect-

ing a calling line to one of said switches, a control device at said one office common to all groups of lines, means for associating said control device with said switch, a plurality of routing relays in said device, means for operating one of said relays in accordance with the zone in which the wanted office lies, means operative under the control of said relay, if said calling line belongs to 10 certain groups, to direct the operation of

said switch to select one route, and means under the control of said associating means, effective if said line belongs to other groups to release said relay and to operate a different relay to direct the operation of said 15 switch to select a different route.

In witness whereof, I hereunto subscribe my name this 19th day of April, A. D. 1927.

WARREN W. CARPENTER.
